Jesse S. Downs, Houston, Tex., assignor to
W-K-M Company, Inc., Houston, Tex.

Application November 11, 1944, Serial No. 116,282

Term of patent 14 years

(Cl. D91—1)

To all whom it may concern:

Be it known that I, Jesse S. Downs, a citizen of the United States of America, residing at Houston, in the county of Harris and State of Texas, have invented a new, original, and ornamental Design for a Valve, of which the following is a specification, reference being had to the accompanying drawing, forming part thereof.

Fig. 1 is a front elevation of a valve, showing my new design.

Fig. 2 is an end view of the valve, and
Fig. 3 is an underside plan view of the valve.
I claim:
The ornamental design for a valve, as shown.

JESSE S. DOWNS.
